(57) **CLAIM**

The ornamental design for an automobile, toy replica and/or other replicas as shown and described.

DESCRIPTION

FIG. 1 is a front and right perspective view of an automobile, toy replica and/or other replicas, showing our new design;

FIG. 2 is a rear and right perspective view thereof;

FIG. 3 is a right side elevation view thereof;

FIG. 4 is a left side elevation view thereof;

FIG. 5 is a front elevation view thereof;

FIG. 6 is a rear elevation view thereof; and,

FIG. 7 is a top plan view thereof.

The broken line showing is included for the purpose of illustrating portions of the automobile, toy replica and/or other replicas and forms no part of the claimed design.
